G. CROSSLAND

TUBE FRAME FOR AXMINSTER LOOMS

Filed Dec. 26, 1924

FIG. 1.

FIG. 3.

Fig. 2.

Inventor
George Crossland

By Watson, Coit, Morse
and Grindley Attorney

UNITED STATES PATENT OFFICE.

GEORGE CROSSLAND, OF AMSTERDAM, NEW YORK, ASSIGNOR TO MOHAWK CARPET MILLS, INC., OF AMSTERDAM, NEW YORK, A CORPORATION OF NEW YORK.

TUBE FRAME FOR AXMINSTER LOOMS.

Application filed December 26, 1924. Serial No. 758,282.

To all whom it may concern:

Be it known that I, GEORGE CROSSLAND, a citizen of the United States, and residing at Amsterdam, county of Montgomery, 5 State of New York, have invented certain new and useful Improvements in Tube Frames for Axminster Looms, of which the following is a specification.

This invention relates to looms for weaving tufted fabrics, such as, for example, Axminster rugs, and relates more particularly to an improved construction of the tube frames for supporting the spools of tuft yarn.

15 In the operation of such looms, the tube frames are carried upon an endless chain, to which they are detachably secured by spring hooks or clamps. These tube frames are removed from the chain in regular sequence by clutch or transfer members which 20 press upon the spring hooks and thereby release the frames from the chain. A portion of the yarn carried by the spool held in the frame is woven into the fabric, and the 25 frame is then automatically replaced upon the chain. It will be seen that it is extremely important that these spring hooks be reliable in operation, and not subject to breakage. The tube frames are also usually 30 provided with a spring brake or tension finger adapted to prevent the yarn carrying spool from rotating too freely.

This invention has for its object to provide a tube frame having an improved construction of such spring hooks or clamps and spring tension fingers.

It is an object of this invention to provide a spring hook which has a greater length than the ordinary spring hook now 40 in use, and hence a greater flexibility when made of a given material, and which will therefore allow the use of a heavier and stronger material than is usual without loss of flexibility.

45 It is a further object of my invention to provide a spring hook which is completely enclosed and protected from breaking influences except at the point where it is essential that it be exposed to the action of the clutch members.

Another object of my invention is to provide an improved spring tension brake for the spool, which is capable of easy and positive adjustment, as required, thereby se-

curing uniform and permanent retarding 55 action.

Other objects and advantages of my invention will be apparent from the following description, taken in conjunction with the accompanying drawings, which form a part 60 of this specification, and in which—

Figure 1 is a side elevation of one end of a tube frame, showing my invention applied thereto;

Figure 2 is an enlarged end elevation of 65 the same;

Figure 3 is a central longitudinal section of a portion of Figure 1, drawn to the same scale as Figure 2; and

Figure 4 is a detail cross-sectional view, 70 taken on the line 4—4 of Figure 1.

Referring more particularly to the drawings, in which like reference characters denote like parts throughout the several views thereof, 10 represents the body or bar of 75 the tube frame, ordinarily constructed of wood, to which are attached the tubes 11. To the upper side of the member 10 at an end thereof is secured a right angle bracket 12, whose upper end is provided with an 80 open-ended slot 13, which serves as a bearing for the axial shaft end 15 of the yarn spool 14. The shaft 15 is prevented from falling out by a flat, hook-shaped, spring member 16, which is pivoted on the rivet 17, 85 and closes the upper end of the slot.

An ear or bracket 18 is fastened to the under side of the end of the member 10 by a screw 19, and forms a part of the clamp by which the tube frame is supported on 90 the chain, as above described. The ear 18 is offset at its upper end, as shown, to form one member of the chain engaging clamp.

A spring hook 20 is fastened in a groove 95 cut in the underside of the bar 10 near the end thereof, and is held in place by means of the ear 18 and the screw 19. The spring hook 20 is preferably made of flat spring steel, and comprises a base portion, which is secured to the bar 10, an arcuate portion bent upwardly in a gradual curve of relatively large radius, and a straight main portion arranged at an obtuse angle to the base portion. The free upper end of the main portion is bent over to form a hook 21, 100 which cooperates with the offset portion of ear 18 and is adapted to engage the carrying chain.

The groove in the bar 10 forms a seat for the end of the spring, and the end of the bar is rounded off as a continuation of the groove, as shown, in order not to interfere with the action of the spring. A hole 22 is provided in the upper end of the spring hook 20, to clear the shaft end 15 when the spring is pressed inwardly by the clutch or transfer members. The spring 20 passes through a long slot 23 in the ear 18 in such a manner that both of its ends are protected from breaking influences, and only that portion of the spring is exposed which must be gripped by the clutch arms. The bracket 12 and the ear 18 may, if desired, be joined together by spot welding or otherwise to form a single unitary structure which may be mounted in place at the same time as the spring hook 20 by slipping the entire assembly endwise on the bar 10. The spring 20 will thus enter the groove provided for it, and the retaining screws may then be inserted. The outer faces of the bracket 12 and ear 18 are preferably mounted flush with the bar 10, as shown.

The other end of the tube frame, not shown in the drawings, is of substantially similar construction, except that the bracket corresponding to bracket 12 is formed with a hole instead of a slot, and the slot 13, catch 16, and rivet 17 are eliminated, as is usual in such constructions.

It is customary to provide one end of the tube frame with a spring brake to check the rotation of the yarn spool. My spring brake is of a new and improved form, which may be easily and positively adjusted to secure a uniform retarding action. It comprises a long tension spring 24, which carries at its free end a friction pad 25, preferably of leather, bearing upon the head 26 of the yarn spool 14. A shorter sub-tension spring 27 is mounted under the tension spring 24, and both springs are fastened to the bar 10 by screws 28 remote from said head. A headless adjusting screw 29 is preferably tapped into both the wooden bar 10 and a nut 30 embedded in the bar, and bears against the sub-tension spring 27. The screw 29 is of such length as not to project below the bar 10, and its lower end is provided with a slot, as shown, to receive a screw driver. By adjustment of the screw 29, the friction on the spool 14 may be easily and permanently regulated.

Various modifications and alterations may be made in my invention without affecting the spirit thereof, and I desire to be limited, therefore, only by the prior art and the scope of the appended claims.

Having thus described my invention, what is claimed as new and desired to be secured by United States Letters Patent is:

1. In a tube frame, in combination, a bar having tubes secured thereto, an ear having

a slot therein secured to the under side of said bar, and a spring hook having a base portion fastened between the under side of said bar and said ear and a main portion extending upwardly thru said slot in said ear. 70

2. The combination as specified in claim 1, in which said base portion of said spring hook is arranged at an obtuse angle to said upwardly extending main portion, and the intermediate portion is in the form of a 75 gradual curve.

3. In a tube frame, in combination, a bar having tubes secured thereto, a right angle bracket having one arm secured to the under side of said bar at one end thereof and the other arm extending upwardly therefrom, the upwardly extending arm having an offset portion adapted to form one element of a clamp, an elongated slot in said upwardly extending arm and said offset portion, and a spring hook adapted to form the other element of said clamp passing through said slot and secured at its lower end between the under side of said bar and said bracket, whereby a relatively long spring is secured 90 which is protected substantially completely from breaking influences.

4. In a tube frame, in combination, a bar having tubes secured thereto, an ear having a slot therein secured to the under side of said bar, a groove formed in said bar adjacent said ear, and a spring hook fastened in said groove between said ear and said bar and extending upwardly thru said slot in said ear, said spring being bent upwardly 100 in a gradual curve.

5. The combination as specified in claim 4, in which the end of said bar within said ear is rounded off to provide an enclosed space for the arcuate portion of said spring. 105

6. In a tube frame, in combination, a bar having tubes secured thereto, a tuft yarn spool supported on said bar, an elongated flat steel spring secured at one end to the upper face of said bar and having its other end bearing on said spool, and an adjusting screw passing thru said bar at right angles to, and bearing upon, said spring. 110

7. In a tube frame, in combination, a bar having tubes secured thereto, a tuft yarn spool supported on said bar, an elongated flat steel spring secured at one end to the upper face of said bar and having its other end bearing on said spool, a second flat spring arranged beneath part of said first spring, a nut embedded in said bar beneath said springs, and an adjusting screw passing thru said nut and bearing upon said second spring at right angles thereto, said adjusting screw being entirely within said bar. 115 120 125

8. As an article of manufacture, a spring hook for use with tube frames, comprising a base portion, an arcuate portion bent upwardly in a gradual curve, the length of said arcuate portion being approximately 130

one-quarter of the total length of the spring, a straight main portion arranged at an obtuse angle to said base portion, and a hook formed on the free end of said spring.

5 9. As an article of manufacture, a spring hook for use with tube frames, comprising a base portion, an arcuate portion bent upwardly in a gradual curve of large radius, the length of said arcuate portion being

more than one-sixth of the total length of 10 the spring, a straight main portion arranged at an obtuse angle to said base portion, and a hook formed on the free end of said spring.

In testimony whereof I hereunto affix my 15 signature.

GEORGE CROSSLAND.
